[57] CLAIM

The ornamental design for a base for a barstool, as
shown and described.

DESCRIPTION

FIG. 1 is a side elevational view of a base for a barstool, showing my new design, the broken lines being for
environmental purposes only and forming no part of the
claimed design;

FIG. 2 is a cross-sectional view taken from line 2—2 in
FIG. 1; and,

FIG. 3 is a perspective view of a second embodiment.
